UNITED STATES PATENT OFFICE.

CHARLES R. TWITCHELL, OF ARTESIA, CALIFORNIA, ASSIGNOR OF ONE-HALF TO
EDMUND A. MILLER, OF LOS ANGELES, CALIFORNIA.

TRACTION-WHEEL.

1,270,991.

Specification of Letters Patent.

Patented July 2, 1918.

Application filed April 11, 1917. Serial No. 161,225.

To all whom it may concern:

Be it known that I, CHARLES R. TWITCHELL, of Artesia, in the county of Los Angeles and State of California, have invented certain new and useful Improvements in Traction-Wheels; and I do hereby declare the following to be a full, clear, and exact description of the invention, such as will enable others skilled in the art to which it appertains to make and use the same.

My invention relates to that class of carrying and laying wheels provided with a track over which the wheels roll and which is automatically laid down and taken up as the wheel progresses and has particular reference to the joint, the connection between the shoes constituting the track, and the rim of the wheel.

In the accompanying drawing, Figure 1 is a side elevation of a traction wheel embodying my invention. Fig. 2 is section on the line 2—2, Fig. 1, and Fig. 3 is a perspective of one of the shoes.

Referring to the drawing the shoes 1 are arranged in two series of staggered disposition as well known in the art, that is, the shoe of one series overlaps the adjacent edges of the shoes of another series. They are mounted in the rim of a traction wheel 2 driven by any appropriate mechanism.

With the view to providing an efficient and removable joint or connection between the shoes 1 and the wheel 2 I construct each of the shoes of three parts. The part 3 is a metal casting and the parts 4 are blocks bolted to the casting at each of its sides as at 5. The casting 3 has formed integrally with it a link 6 which passes through a slot 7 in the flange 8 of the wheel rim. At the inner extremity of this link is a knob 9 loosely held on the link by a pin 10, the knob being preferably rabbeted to receive the end of the link. As shown in Fig. 2, the knob is wider than the slot 7 in the wheel rim so that when the shoe 12 is in the position of Fig. 1 it will be held as against falling out. This enables me to make the slot 7 long enough to insure the necessary swing of the link and shoe.

The knob is shown of convex formation as at 13 to provide a rolling surface which insures the shoe gravitating into the proper position on reaching the ground.

The link 6 has its edges curved so as to cause the link to taper bodily toward the knob 9. This curvature varies with the diameter of the wheel. Its purpose is to provide a formation which will co-act with the convex surface of the loosely mounted knob 9 to adapt the link to the curvature of the wheel and to the angles the shoes assume relatively to the wheel, and thereby lessen friction.

It will be understood that the described link connection applies to all of the shoes, and that the primary advantages are the readiness with which shoes may be removed and replaced by withdrawing the pins 10, and the reduction of friction in the swing of the shoes.

I claim as my invention:

1. In a traction wheel, the combination with a wheel rim having a slot, of a tread shoe having a link passed through said slot, and a knob loosely mounted on the inner end of the link, said link having its edges curved to taper the link toward the knob.

2. In a traction wheel, the combination with a wheel rim having a slot, of a tread shoe having a link passed through said slot, and a knob of convex formation to provide a rolling surface on the wheel rim and loosely mounted on the inner end of the link, said link having its edges curved to taper the link toward the knob.

3. In a traction wheel, the combination with a wheel rim having a slot, of a tread shoe comprising a pair of blocks and a casting between and secured to said blocks, a link integral with said casting and passed through said slot, and a knob fulcrumed on the inner end of said link.

4. In a traction wheel, the combination with a wheel rim having a slot, of a tread shoe comprising a pair of blocks and a casting between and secured to said blocks, a link integral with said casting and passed through said slot, and a knob fulcrumed on the inner end of said link, said knob being wider than said slot and of convex formation to provide a rolling surface on the wheel rim.

5. In a traction wheel, the combination with a wheel rim having a slot, of a tread shoe comprising a pair of blocks and a casting between and secured to said blocks, a

- link integral with said casting and passed through said slot, said link having its edges curved to taper the link, and a knob fulcrumed on the inner end of said link, said 5 knob being wider than said slot and of convex formation to provide a rolling surface on the wheel rim.

In testimony whereof, I have signed this specification in the presence of two subscribing witnesses.

CHARLES R. TWITCHELL.
